UNITED STATES PATENT OFFICE

168,711

PLATTER OR SIMILAR ARTICLE

William C. Richardson, Los Angeles, Calif., assignor to Technical Porcelain and Chinaware Co., El Cerrito, Calif., a partnership

Application August 28, 1952, Serial No. 21,221

Term of patent 14 years

(Cl. D44—15)

To all whom it may concern:

Be it known that I, William C. Richardson, a citizen of the United States of America, residing in the city of Los Angeles and county of Los Angeles and State of California, have invented a new, original, and ornamental Design for a Platter or Similar Article, of which the following is a specification, reference being had to the accompanying drawing, forming part thereof.

This case is a continuation-in-part of application Number D. 11,010, filed on July 8, 1950, which is now abandoned.

The figure of the drawing shows a platter or similar article of conventional configuration embodying my new design.

The dominant feature of my design resides in the surface ornamentation of the platter or similar article.

I claim:

The ornamental design for a platter or similar article, substantially as shown and described.
WILLIAM C. RICHARDSON.
